UNITED STATES PATENT OFFICE.

ALBERT EDGAR BEEBE, OF CATHAY, NORTH DAKOTA.

APPARATUS FOR MARINE PROPULSION.

Application filed January 14, 1922. Serial No. 529,331.

To all whom it may concern:

Be it known that I, ALBERT EDGAR BEEBE, a citizen of the United States, and a resident of Cathay, in the county of Wells and State of North Dakota, have invented certain new and useful Improvements in Apparatus for Marine Propulsion, of which the following is a specification.

This invention relates to an improvement 10 in apparatus for marine propulsion.

The object of the invention is to provide an apparatus of this character which is adapted to operate either as a tractor or as a propeller and which in either event operates to efficiently propel or drive the boat in such a manner as to develop a maximum degree of efficiency from a minimum expenditure of power.

Another object is to provide an apparatus 20 of this character wherein means is provided for readily and easily reversing the propellers without shifting the engine or power plant used to drive the same.

Another object is to provide a device of 25 this character which is of simple and durable construction, reliable in operation and easily and comparatively inexpensive to manufacture.

Other objects and advantages of the invention reside in certain novel features of 30 construction, combination and arrangement of parts which will be hereinafter more fully described and particularly pointed out in the appended claims reference being had to 35 the accompanying drawings forming part of this specification, and in which:

Figure 1 is a fragmentary view in side elevation, illustrating one end of the boat equipped with the marine propelling apparatus which constitutes the present invention;

Figure 2 is a diagrammatic view in bottom plan;

Figure 3 is a view in transverse vertical section taken approximately on line 3—3 of Figure 1;

Figure 4 is a fragmentary perspective view, illustrating the propeller and its connection to the shiftable carrier and the reciprocating frames;

Figure 5 is a diagrammatic view in plan illustrating the reversing means of the propellers, and showing the propellers positioned or set for "forward,"

Figure 6 is a view similar to Figure 5, 55 showing the propellers set or positioned for "reverse,"

Figure 7 is a fragmentary view, partly in section and partly in elevation, illustrating the driving mechanism and shifting mechanism for the propellers;

Figure 8 is a fragmentary detail view in plan of the shifting mechanism;

Figure 9 is a view of a modified form of the invention adapted only for one way 65 movement.

Referring to the drawings wherein for the sake of illustration is shown the preferred embodiments of the invention and more particularly to Figures 1 to 9, inclusive, the 70 reference character B designates a boat which may be of any desired type and which is equipped at one or both ends with the propulsion apparatus constituting the present invention. The propulsion apparatus 75 is designated generally at P and is arranged adjacent the end of the boat, the extreme end of the boat being equipped with a guard G consisting of angularly arranged series of spaced and parallel bars or plates, indicated at g. Between the propulsion apparatus and the guard G a rudder, designated at R is arranged.

The propulsion apparatus which constitutes the present invention may be provided 85 at each end of the boat and each propulsion apparatus preferably includes two units indicated at P' and P², the units being superposed or arranged one above the other and driven from separate power plants or engines, the arrangement being such that when the unit P' is driving or propelling, the unit P² is feathering and vice versa. A single stationary or main frame F is secured to the boat, as shown in Figure 1 and 90 serves to support both the units P' and P², the frame F including for this purpose an upper channel-way 10, a lower channel-way 11, and an intermediate or central channel-way 12, the channel-ways 10, 11 and 12 being connected to end pieces or frame members 13 and 14 to complete the main or stationary frame F. The unit P' operates in the channel-ways 10 and 12 of the stationary frame and the unit P² operates in 100 the channel-ways 12 and 11 of the stationary frame, and as these units P' and P² are of identical construction, a common description

will serve for both. Each of the propulsion units includes a reciprocating frame, designated generally at 15 and comprising upper and lower longitudinally extending bars, indicated at 16 and 17, respectively, and end bars 18 and 19, respectively, the end bars being rigidly connected with the longitudinal bars. The upper and lower longitudinal bars 16 and 17 operate in the channel-ways of the stationary frame member, and if desired suitable anti-friction means may be provided between these channel bars and the frame members, the anti-friction means comprising roller bearings 20 and ball bearings 21 or other suitable devices. A shiftable propeller carrier, designated generally at 25, is mounted on the reciprocating frame, the carrier being received in slide-ways 26 and 27 provided in longitudinal bars 16 and 17 of the reciprocating frame. Anti-friction means such as roller bearings 28 and ball bearings 29 or other suitable anti-friction devices may be provided between the carrier and the slideways of the reciprocating frame.

A plurality of propellers, denoted generally at 30, are pivotally supported upon angle bars 31 secured to the propeller carrier. The propellers 30 are preferably arranged in series on each side of the carrier and the propellers on one side of the slideable frame are preferably aligned with the propellers on the other side thereof. Obviously, any number of propellers may be employed. Each propeller comprises a vane or imperforate plate of metal, designated at 32, and wings 33 integral with or suitably secured to said vanes. Stays 35 and 36 are provided for each propeller, and each set of stays have their outer ends pivotally connected to their propeller and at their inner ends have sliding connections with flanges 37 provided on the reciprocating frame 16. Preferably a pair of stays 35 is provided for each propeller and both stays 35 operate on one side of their propeller. Similarly, a pair of stays 30 are provided for each propeller and operate on the opposite side of the propeller. The sliding connection between the stays 35 and the flanges of the reciprocating frame is constituted by forming elongated slots 38 in the flanges and arranging sliding blocks 39 in said slots for reciprocatory movement and pivotally connecting these sliding blocks 39 with the stays 35. Similarly the stays 36 have sliding connection with the flanges 37 of the reciprocating frame by providing slots 40 in the flanges and arranging sliding blocks 41 in the slots 40 and pivotally connecting these sliding blocks to the stays 36. The ends 38^a and 40^a of the slots present abutments with which the sliding blocks 39 and 41 respectively engage at certain times, as will be hereinafter more fully described. It is to be understood of course that when

the sliding block 39 of the stay 35 is engaged with the abutment 38^a that the sliding block 41 is not engaged with the abutment 40^a and vice versa. Obviously, the engagement of the sliding blocks with their abutments may be controlled by shifting the propeller carrier relative to the main frame so as to thereby bring about relative movement between the slots 38 and 40 and the blocks 39 and 41. When the slots 38 and 40 are so disposed with respect to the sliding blocks 39 and 41 that the sliding blocks 39 are not engageable with the abutment 38^a of the slots 38 and the sliding blocks 40 are engageable with the abutments 40^a of the slots 40, the propellers or vanes 30 are effective to propel or drive the boat in the direction shown by the arrow in Figure 5, that is "forward" if the propulsion apparatus is arranged at the stern of the boat. This is due to the fact that the reciprocating frame and carrier are actuated as a unit as will be hereinafter more fully described so that when the reciprocating frame is moved to the right in Figure 5 the propellers 30 will be effective to impel the boat as after they are in a position at right angles to the carrier as shown in full lines in Figure 5, they are held against further swinging motion due to the staying action of the stays 36 exerted by virtue of the engagement of the sliding blocks 41 of these stays 36 with the abutments 40^a of the slots 40. When the reciprocating frame is driven in the opposite direction that is to the left as viewed in Figure 5 the propellers or vanes 30 swing to the position shown in dotted lines or feather, and they are free to partake of this motion under the action of the water since the sliding blocks 39 may freely move in their slots 38 and since the sliding blocks 41 may move in the slots 40 away from the abutments 40^a.

On the other hand when the carrier has been shifted so that the slots 38 and 40 have been moved relative to the sliding blocks 39 and 41 so that the sliding blocks 39 are engageable with the abutments 38^a whereas the sliding blocks 41 are not engageable with the abutments 40^a the propellers will be in reverse that is they will be effective to move the boat in the direction indicated by the arrow in Figure 6. At this time when the reciprocating frame is moved to the left in Figure 6, the stays 35 are effective to hold the propellers or vanes 30 in a position at right angles to the reciprocating frame and the carrier 25 as shown in full lines in Figure 6 since the sliding blocks 39 are engaged with the abutments 38^a of the slots 38. However, when the reciprocating frame and carrier are moved to the right as viewed in Figure 6 the propellers 30 feather that is they swing over to the position shown in dotted lines. This swinging movement being due to the action of the water since the

sliding blocks 39 are free to slide to the right that is away from the shoulders 38^a and since the sliding blocks 41 freely move in their slots 38 to accommodate this movement of the vanes.

Any suitable form of power plant may be utilized for driving the reciprocating frame of each power unit and for the sake of illustration one means which may be employed 10 is shown in Figure 7. In this form a steam engine, designated at 50, is provided and may be of any standard or conventional type. The piston rod 51 of the engine is connected to a cross head 52 operating in 15 cross head guides 53. A yoke frame 54 including spaced and parallel bars 55 and 56 is connected at one end of the cross head and at the other end to a hollow rod 57 which operates through suitable packing 58 20 and which is connected to the reciprocating frame 15 by means of a coupling or connection 59. By this mechanism the engine 50 is effective to actuate the reciprocating frame 15.

Shifting mechanism is provided for moving or shifting the propeller carrier 25 relative to the reciprocating frame in order to vary the action of the propellers and this shifting mechanism also constitutes means 30 for securing the carrier in adjusted position relative to the reciprocating frame so that the carrier is constrained to partake of the motion of the reciprocating frame and moves therewith as a unit. This means preferably 35 comprises a rod 60 suitably connected as at 61, to the carrier and extending through the hollow rod 57, suitable packing being employed between the hollow rod 57 and the rod 60. The inner end of the rod 60 operates 40 between the bars 55 and 56 of the yoke 54, and this inner end carries a head 62 to which a T-shaped bar 63 is pivotally connected. The arms 64 and 65 of the T-shaped bar constitutes means whereby the 45 rod 60 may be moved, and these arms are also adapted to be received in slots 66, 67 and 68 provided in the bars 55 and 56 and to be held in any one of these slots by means of latching means 69. When the arms 64 50 and 65 are seated in the slots 66, the propeller blades are in "reverse." When they are seated in the slots 67, the propeller blades are in "neutral" and will idly flap back and forth. When these blades are in 55 the slots 68, the propeller blades are in "forward."

Obviously, the propulsion apparatus which constitutes the present invention may be arranged at the stern as indicated in the 60 description of the operation of the reversing mechanism but it may be arranged at the bow, or again one such apparatus may be arranged at the stern and another may be arranged at the bow of the same boat.

65 In the form of the invention shown in

Figure 10 the means for reversing the action of the propeller is omitted and the propeller or vane which is designated at 75 is pivotally mounted on a frame 76 which is itself mounted for reciprocatory movement 70 driven from any suitable form of power plant. Thus the shiftable propeller carrier is omitted in this embodiment of the invention and the frame 76 itself constitutes the reciprocating frame and corresponds to 75 the reciprocating frame 15 of the embodiment of the invention shown in Figs. 1 to 8 and hereinabove described. The frame 76 has flanges or bars 77 extending longitudinally thereof and provided with slots 78. A single set of stays, designated at 79 is provided, and these stays 79 are pivotally connected at one end, as at 80, and having sliding blocks 81 pivoted to their opposite ends and received for reciprocatory motion in the 85 slots 78. One end of the slots 78 constitutes an abutment for the sliding block and this abutment is designated at 83. It is obvious when the frame 76 is moved in one direction, the propeller or vane 75 will be held 90 in position at right angles to the frame by virtue of the staying action of the stays since at this time the sliding blocks of the stays are engaged with the abutments of the slots. When however the frame is moved 95 in the opposite direction the propeller will feather as it is free to swing over against the frame since the sliding blocks are free to move away from the abutments to accommodate this movement.

It is obvious that while only one form of 100 sliding connection is shown in conjunction with both embodiments of the invention any suitable or well known type of connection of this character may be utilized, and it is 105 obvious that various other changes in the form, proportions and minor details of construction may be resorted to without departing from the spirit of the invention or the scope of the appended claims.

I claim:

1. In a marine propulsion apparatus including a main frame having channelways therein, a reciprocating frame operating in said channelways, means for imparting reciprocatory movement to said reciprocating frame, said reciprocating frame having slideways therein, a shiftable propeller carrier operating in said slideways, means for moving said carrier relative to said reciprocating frame and for locking said carrier in adjusted position, a series of propellers pivotally connected to said carrier, flanges carried by said reciprocating frame and having slots therein on each side of each of 115 said propellers, one end of each of said slots constituting an abutment, a set of stays co-operating with each of said propellers from each side thereof, each of said stays being pivotally connected at their outer ends to 120 125 130

said propellers, a sliding block pivotally connected to the inner end of each of said stays and received for sliding motion in the adjacent slot of the flange of the reciprocating frame.

2. In an apparatus of the character described, a reciprocating frame, a propeller carrier, means for adjusting said carrier relative to said reciprocating frame and for securing said carrier in adjusted position, a propeller pivotally connected to the carrier, flanges carried by the reciprocating frame having slots therein on each side of said propeller, stays pivotally connected at their outer ends to the propeller, one of said stays operating on one side of said propeller and the other of said stays operating on the other side and sliding blocks pivotally connected to the inner ends of the stays and operating in the slots of the flanges, each of the slots having one end constituting an abutment, either of said abutments being adapted to be positioned to be engaged by the sliding block operating in its slot, the engagement of one of said abutments or the other of said abutments with its sliding block being controlled by the adjustment of said shiftable propeller carrier.

3. In an apparatus of the character described, in combination with a boat, a stationary frame mounted upon said boat, a reciprocating frame operating on said stationary frame, a shiftable propeller carrier mounted on said reciprocating frame, propellers pivotally secured to the carrier and adapted to be reversed by movement of said carrier relative to said reciprocating frame, means for reciprocating said reciprocating frame including a yoke frame, a tubular rod connecting said yoke frame and said reciprocating frame, and means for shifting said carrier relative to said reciprocating frame and for securing said carrier in adjusted po-

sition comprising a rod slidably extending through the hollow rod and connected to said carrier, and a T-shaped bar pivotally connected to said rod, said yoke frame having a series of notches therein cooperable with said T-shaped bar for locking the same in adjusted position.

4. In an apparatus of the character described, in combination with a boat, a main frame having an upper channelway, a lower channel, and intermediate channelways, a propelling unit operating in the upper channelways and one of the intermediate channelways, a second propelling unit operating in the lower channelway and the other intermediate channelway, separate power means for each of said propelling units, each of said propelling units including a reciprocating frame, a shiftable propeller carrier, a series of swinging vanes, and means for limiting the movement of said swinging vanes in one direction.

5. In an apparatus of the character described, a reciprocating frame, a shiftable propeller carrier mounted thereon, a swinging propeller pivotally mounted on the carrier, stays pivotally connected at their outer ends to said propeller, one of said stays operating on one side of said propeller and the other of said stays operating on the other side thereof, sliding connections between the inner ends of said stays and said reciprocating frame, said reciprocating frame having an abutment for each of said sliding connections, either of said abutments being adapted to be brought into position to be engaged with the sliding connection or to be moved beyond the distance traversed by its sliding connection upon movement of said shiftable propeller carrier, whereby said propeller may be reversed.

ALBERT EDGAR BEEBE.
